UNITED STATES PATENT OFFICE.

MARTIN JONES, OF SAN DIEGO, CALIFORNIA.

DESIGN FOR A WRITING PEN.

61,041.

Specification for Design.

Patented June 6, 1922.

Application filed May 27, 1921. Serial No. 473,155. Term of patent 3½ years.

To all whom it may concern:

Be it known that I, MARTIN JONES, a citizen of the United States, residing at San Diego, in the county of San Diego and State of California, have invented a new, original and ornamental Design for a Writing Pen, of which the following is a specification, reference being had to the accompanying drawing, forming part thereof.

In the drawings the single figure is a front elevation of my writing pen.

I claim:

The ornamental design for a writing pen, as shown.

MARTIN JONES.
